Primary Examiner — Rosemary K Tarcza*Assistant Examiner* — Christy Nemeth(74) *Attorney, Agent, or Firm* — Taylor IP, P.C.(57) **CLAIM**

The ornamental design for a desktop receptacle cover, as shown and described.

DESCRIPTION

FIG. 1 is a top view of a desktop receptacle cover shown in the environment of a desktop receptacle;

FIG. 2 is a front view thereof;

FIG. 3 is a side view thereof;

FIG. 4 is a rear perspective view thereof;

FIG. 5 is a bottom view thereof;

FIG. 6 is a second top view of the desktop receptacle cover, shown without environment for ease of illustration; and,

FIG. 7 is a cross-sectional view thereof taken along the line 7-7 in FIG. 6.

In the drawings, the broken lines are for the purpose of illustrating environment only and form no part of the claimed design.

1 Claim, 4 Drawing Sheets(56)
